UNITED STATES PATENT OFFICE.

ADOLPH E. SCHURCH, OF LOS ANGELES, CALIFORNIA.

FOOTBALL-GAME APPARATUS.

Application filed August 30, 1926. Serial No. 132,343.

This invention relates to a game apparatus to enable two players to play a game simulating football, and in which the plays are determined by chance. The general object 5 of the invention is to provide a simple apparatus including a game board representing the football field, and provided with devices located generally at each side of the board so that there will be a set of the devices corresponding to each player; also to provide 10 a chance device capable of being operated readily by each of the players and to provide a compact arrangement for the game board and apparatus carried by it to facilitate the 15 playing of the game and the indicating of the scores of the players.

In the playing of the game, a small die representing the football is placed at different points on the field, as indicated by 20 the play which has been determined by chance, and one of the objects of the invention is to provide the board with means along the side of the football "field" which will indicate plays which would be appropriate to the regular game of football when 25 the ball is in a certain location on the field.

Further objects of the invention will appear hereinafter.

The invention consists in the novel parts 30 and combination of parts to be described hereinafter, all of which contribute to produce an efficient football game apparatus.

A preferred embodiment of the invention is described in the following specification, 35 while the broad scope of the invention is pointed out in the appended claims.

In the drawings:

Figure 1 is a plan of a game apparatus embodying my invention.

40 Figure 2 is a vertical section taken through one end of the board and indicating a score-board which constitutes a feature of the invention.

Figure 3 is an ideal section taken about 45 on the line 3—3 of Fig. 5, particularly illustrating the construction of the chance device.

Figure 4 is a plan of the cover of the chance device, and particularly illustrating 50 the use of distinctive characters for determining the play to be made by the player.

Figure 5 is a plan of the chance device with its cover removed and indicating details of the construction of this device.

55 Figure 6 is a plan showing the bottom

plate of the chance device with details of its construction.

Figure 7 is a plan illustrating the face of one of the dials which I employ on the apparatus.

Figure 8 is a similar view showing another dial located at another point on the board.

Figure 9 is a view on the line 9—9 of Figure 8.

In its construction, the apparatus includes a rectangular "board" 1 which may be constructed of any suitable rigid material. On the central longitudinal axis of this board, a football "field" 2 is represented by side 70 lines 3 and transverse ten-yard lines 4, which are numbered consecutively in the usual manner. At each end of the field, goals 5 are indicated by lines on the face of the board.

75 On each side of the board, I provide a row of dials 6. The dials on one side are to be used by one of the players and the dials on the other side by the other player. These dials include intermediate dials which are located opposite the different yard lines of the field and end dials 7 and 8. There are two of the dials 7 which are located in diametrically opposite corners, and likewise 80 there are two of the dials 8 located in diametrically opposite corners. The dials 7 are alike. Each of these dials is divided into sectors 9 and these sectors carry different legends corresponding to different football plays which would be made at the time of 85 the kick-off and return of the ball. Adjacent each of these dials the board carries a legend indicating this.

90 Each dial 7 is provided with a movable member, for example, a disc 10 with a gap 95 11 of sector form. This disc may be rotated by means of a central button 12 so as to bring this gap 11 over any one of the sectors 9.

95 A small pea or "die" 13 is used to represent a football and it may rest at any point on the field to indicate the present position 100 of the ball during the game. The player sitting at the lower side of the board, as indicated in Fig. 1, would use the dial 7 at 105 the left in making his first play. In other words, this dial is located near the end of the board where the ball is supposed to be kicked off.

110 The dials 6 are formed with sectors 14

having different legends to indicate different football plays which would be appropriate in the game when the ball is located opposite to any certain dial, for example, in Fig. 5 1, supposing the arrow near the die indicates the direction the ball is to go during the play, then the left-hand dial 6 on the ten-yard line would be used to indicate the proper play, and the legends on this dial 10 would be appropriate to this position of the ball on the field.

In the present instance, these intermediate 15 dials are located on alternate yard lines, and are consequently five in number. The right-hand dial (for each player) of the intermediate dials has a legend near it on the board reading "Run and pass" and "Point after touchdown", and the legends on the sectors 15 of this dial would be appropriate 20 to the playing of the game if the ball were on this ten-yard line before the right-hand goal and being advanced toward this goal. The other intermediate dials have the title 25 "Punt and return—Run and pass". The legend on the board corresponding to the dials 8 is "Drop or place kick", and the legends on the sectors 16 of these dials 8 indicate plays corresponding to drop and place kicks.

30 Every dial is provided with a movable member, such as the disc 10, with a central button for rotating the disc into any position which may be indicated by a chance device 17 which is located on the board, and 35 preferably at the left end beyond the end of the field. This chance device is intended to operate with a marble or ball which is projected along a raceway and comes to rest in some position determined by chance or by 40 the force with which the ball is projected. This chance device is constructed of a block 18 having a continuous raceway 19 which may be oblong or elliptical, and in the bottom of which is formed a series of shallow 45 pockets 20, in any one of which the ball may stop (see Fig. 9). Each pocket is slightly depressed below the bottom 21 of the raceway. The ball or marble may be projected along the raceway by each player.

50 In order to accomplish this, I provide two projecting devices 22 (see Fig. 5), each consisting of a lever 23 pivoted at 24 so that it is capable of swinging to and fro in a sector-shaped gap 25 which is cut in the upper face 55 of the block. In this gap a spring 26 is mounted which bears against the back of the projecting lever 23. On the forward side of the projecting lever 23, a small cup 27 is formed to hold the ball 28. If the thumb 60 piece 29 on the end of the lever 23 is moved in the direction of the arrow near the bottom of Fig. 5, the lever can be swung back toward the position in which it is indicated in dotted lines. This will flex the spring 26 65 and when the lever is released, the spring

will swing it toward the right and the ball carried in the cup will be projected along the raceway 19.

The chance device is provided with a cover 30 over the raceway, and this cover has 70 glazed windows 31 through which the pockets 20 may be seen. Each glazed window has its own distinctive character, for example, these windows may be lettered A, B, C, etc. After the ball 28 has come to rest 75 in a certain pocket and the player has finished his play, the ball may be released so as to enable it to be projected in the raceway by the other player.

In order to accomplish this, I provide a 80 bottom plate 32 which forms the bottom for all of the pockets 20. This plate has a plurality of openings 33 formed in it and located slightly out of alignment with the pockets 20. The plate is further provided with a 85 projecting thumb piece 34 which enables the plate to be rotated about a pivot point 35 which attaches the plate to the under side of the block. A spring 36 is provided for returning this plate to its normal position after 90 it has been moved to open the pockets.

Under the plate 32, a gutter plate 37 is provided which is attached to the under side 95 of the block and this gutter plate inclines toward a delivery point 38, to which point 95 the marble or ball will roll from any point at which it is released.

In Fig. 7, I illustrate one of the intermediate dials 6, and particularly the left-hand dial which is in line with the ten-yard 100 line. The sectors on this dial may carry legends as indicated in Fig. 7 to indicate different plays. In Fig. 8, I illustrated the intermediate dial which is opposite the fifty-yard line and the legends on the sectors of 105 this dial would correspond to plays which the ball should have when located at this point and being advanced toward the right down the field.

In playing the game, after a player has 110 operated the chance device, he observes the pocket in which the ball finally rests, together with the letter or character which is carried on the glazed window above this pocket. This character is a key character 115 which determines what the play will be, for example, if the ball were near the ten-yard line, as indicated in Fig. 1, and the chance device when operated indicated the letter B, then the disc on the face of the dial 6 opposite the ten-yard line would be rotated until its gap came opposite to the letter B on the margin of the dial. If using the outer circle, the play would then be indicated by 120 the legend near the edge of the dial, which is to the effect that No. 5 was offside so that there is a loss of five yards penalty to the player. The ball or die 13 would then be moved five yards to the left. The dials 7 and 8 are operated in the same way as the 130

dials 6 in playing the game, that is to say, when the dials 7 and 8 are used, the position in which their determining disc is placed depends upon the pocket in which the ball 28 finally rests when the projecting device has been used by the player.

On one of the side lines 3, a small indicator 39 may be provided, the length of which represents ten yards. This indicator 10 should have one end placed in alignment with the ball 13 when one of the players has just come into possession of the ball.

At the end of the board opposite the chance device 17, I provide a score-board 40 15 with windows 41 in which the scores may be displayed. The numbers indicating the scores may be carried on dials, the edges 42 of which project so as to enable the numbers to be changed by the players. If desired, this score-board may be constructed so that it can fold down onto the face of the board. For this purpose, the face plate 42 20 of the score-board may be mounted on a hinge pin 43 so that it can swing up out of a pocket 44 in the face of the board. The rear side of the face plate 42 may be provided with one or more triangular shaped brackets 45 attached by hinges 46 to the back of the face plate. Figure 2 shows the 25 manner in which these parts cooperate to hold the score-board set up. Evidently, by folding the bracket or brackets 45 on their hinges, the face plate 42 may be folded down into the plane of the board 1.

35 The cover 30 of the chance device may have a line 47 to represent a seam of the cover of a football, and may also have cross-marks 48 to indicate lacing.

What I claim is:—

40 1. In a football game apparatus having a game board indicating a football field and a pea representing the football, to be placed at different points on the field, the combination of a chance-device with a plurality of 45 different characters located at different points on the same, and any one of which may be indicated when the chance device is operated, a dial having a margin with different characters around the same corresponding to the said different characters of the chance-device, and having an indicating member adapted to be moved into a position corresponding to the character indicated by the operation of the chance device, said dial 55 having means for indicating different plays corresponding to different positions of the said indicating member of the dial.

2. In a football game apparatus having a game board indicating a football field and a pea representing the football, to be placed at different points on the field, the combination of a chance-device with a plurality of 60 different characters located at different points on the same, and any one of which may be indicated when the chance device is 65

operated, a dial on the board adjacent one end of the field, having a margin with different characters around the same corresponding to the said different characters of the chance-device, and bearing legends corresponding to the positions of the different characters around the dial, indicating the yards gained in the kick-off and the yards lost in the return of the ball, and having an indicating member adapted to be moved into 75 a position corresponding to the character indicated by the operation of the chance device.

3. In a football game apparatus having a game board indicating a football field and a pea representing the football, to be placed at different points on the field, the combination of a chance-device with a plurality of different characters located at different points on the same, and any one of which may be indicated when the chance device is operated, a dial adjacent one end of the field for indicating drop, or place, kicks, having a margin with different characters disposed around the same corresponding to the said different characters of the chance-device, with legends corresponding to the said different characters indicating different results from a supposed drop, or place, kick, and having an indicating member movably mounted on the dial adapted to be moved into a position corresponding to the character indicated by the operation of the chance-device.

4. A football game apparatus having a game board with transverse lines representing the yard lines of the field, and a pea representing the football, to be placed at different points on the field, a plurality of dials disposed substantially in alignment with the said yard lines, each dial having a plurality of sectors with legends on the same indicating different plays appropriate to the game when the location of the ball is opposite the dial, each dial having a movable member adapted to be moved to a position determined by chance to indicate a certain sector and thereby indicate the play to be made.

5. A football game apparatus having a game board with transverse ten-yard lines indicating the football field, and a movable pea representing the football, to be placed at different points on the field, a plurality of dials disposed on one side of the board to be used by one of the players and a plurality of dials on the other side of the board to be used by the other player, said dials being disposed respectively opposite the ten-yard lines and each dial having a plurality of sectors with legends on the same corresponding to different plays, and a movable disc associated with each dial having a gap in the form of a sector for exposing a single sector of the dial to determine the play to be made by the player, the legend on any 130

dial indicating appropriate plays to be made in the game when the ball is located near the yard line corresponding to that dial.

6. In a football game apparatus, a game board having a plurality of transverse ten-yard lines representing the football field, a plurality of dials on one side of the board to be used by one of the players, and a plurality of dials on the other side of the board to be used by the other player, one of said dials at one end of the board having sectors with legends indicating plays corresponding to the kick-off and return of the ball when it is first put in play by one of the players, and having a movable member associated with the dial for indicating the play to be made, the dial on the diagonally opposite corner of the said board having sectors with legends indicating different plays appropriate to the kick-off and return of the ball by the adversary when the ball is first put in play, one of said dials at the end of the board having sectors with legends indicating drop, or place, kicks with a movable member for indicating the play to be made when the ball is on the field near the last-named dial, the dial at the diagonally opposite corner on the other side of the board having sectors with legends indicating drop, or place, kicks, and a movable member associated with the same to be used by the adversary.
7. In a football game apparatus, a game board having a plurality of transverse ten-yard lines representing the football field, a plurality of dials on one side of the board to be used by one of the players, and a plurality of dials on the other side of the board to be used by the other player, one of said dials at one end of the board having sectors with legends indicating plays corresponding to the kick-off and return of the ball when it is first put in play by one of the players, and having a movable member associated with the dial for indicating the play to be made, the dial on the diagonally opposite corner of the said board having sectors with legends indicating different plays appropriate to the kick-off and return of the ball by the adversary when the ball is first put in play, one of said dials at the end of the board having sectors with legends indicating drop, or place, kicks with a movable member for indicating the play to be made when the ball is on the field near the last-named dial, the dial at the diagonally opposite corner on the other side of the board having sectors with legends indicating drop, or

place, kicks, and a movable member associated with the same to be used by the adversary, the other dials on each side of the board being located between the end dials and substantially in line with the different yard lines and having sectors with legends indicating plays appropriate to the game when the die is located on the yard line opposite that dial, with a movable member for indicating a certain sector to determine the play to be made.

8. In a football game apparatus, a chance device having a continuous raceway and a ball to move along the same, means for projecting the ball along the raceway, said raceway having a plurality of pockets, in any one of which the ball may stop, said pockets having distinctive characters for determining the play to be made, a pivoted plate forming the bottoms of the pockets and having openings corresponding to the different pockets which may align with the pockets when the plate is moved to permit the ball to fall out of the pocket in which it may lodge.

9. In a football game apparatus, a chance device having a raceway, a ball adapted to run long the raceway, a projecting device for the ball disposed near one side of the game board to be used by one of the players, a second projecting device for the ball disposed toward the other side of the game board to be used by the other player, said raceway having a plurality of pockets, in any one of which the ball may stop, said pockets having different distinctive characters to determine the play to be made by the player.

10. In a football game apparatus, a game board having transverse ten-yard lines indicating the football field, a row of dials on one side of the board to be used for indicating plays by one of the players, a row of dials on the other side of the board to be used to indicate plays by the other player, a chance-device on one end of the board beyond the field having operating means located toward one side of the board operable by one of the players, and having operating means located toward the other side of the board operable by the other player, and a score-board at the other end of the board beyond the field with means for indicating the scores of the players.

Signed at Los Angeles, California this 23 day of August 1926.

ADOLPH E. SCHURCH
